UNITED STATES PATENT OFFICE.

ORIN F. DAY, OF VALLEY, WASHINGTON.

BUCKLE.

1,136,213.

Specification of Letters Patent. Patented Apr. 20, 1915.

Application filed April 16, 1913. Serial No. 761,501.

To all whom it may concern:

Be it known that I, ORIN F. DAY, a citizen of the United States, residing at Valley, in the county of Stevens and State of Washington, have invented new and useful Improvements in Buckles, of which the following is a specification.

My invention relates to an improved form of buckle and has, as its principal object, the 10 production of a buckle which may be attached to a strap without the aid of rivets.

A further object resides in the particular arrangement and combination of parts hereinafter described.

15 In the accompanying drawing:—Figure 1 is a perspective view of my improved buckle. Fig. 2 is a side elevation of the device shown in Fig. 1. Fig. 3 is a view similar to Fig. 2 but showing the belt or strap 20 applied to the buckle.

In the separate views the same part is designated by the same reference character.

Referring more particularly to the drawing, 1 designates my improved buckle which 25 is preferably cast integral with the exception of the hook or prong, and comprises a rectangular frame having two parallel side pieces such as 2 connected at the ends by members 3, it being understood that the 30 parts 2 and 3 lie in approximately the same plane. About midway of the length of the parts 2 is a cross plate 4 lying substantially in the plane of the frame to which the prong or hook 5 is pivoted near one edge. It will 35 be obvious that the prong 5 rests on one of the members 3 at one end of the frame. For purposes of convenience I will call this end of the frame the forward end and the side of the frame on which the prong rests I 40 will call the top. At the rear of the frame 1 and projecting upwardly from the top thereof I provide a bow-shaped piece 6 there being sufficient space between the member 6 and the member 3 at that end of 45 the frame to permit a strap to pass freely therethrough. A bow shaped member 7, similar to 6, is provided which stretches between the members 2 on the underside of the frame at the forward edge of the plate 4.

50 While somewhat less than half the distance from the rear edge of the plate 4 and the rear cross member 3 I provide a cross bar 8, the upper edge of which is flush with the

under face of the frame as clearly shown in Figs. 2 and 3. It will also be seen that the 55 under face of the plate 4 carries a pin 10 projecting downwardly therefrom, the purpose of which will presently appear.

Referring more particularly to Fig. 3, 11 is the end of the strap which is intended to 60 be fixed to the buckle 1 and the end 11 is led between the member 6 and the rear member 3, thence forwardly under the forward member 3, after which it is bent rearwardly and passed through the member 7 above the 65 cross bar 8 and below the rear member 3, the end appearing at 12. It will be understood that the end of the strap 11 is provided with suitable holes through which the prong 5 and the pin 10 may project. After the strap 70 has been woven into the position shown in Fig. 3, the part 11 is pulled rearwardly so that the strap is tightened over the forward end of the plate 4 allowing prong 5 to project in the usual manner so that it may be 75 used for attaching the strap 11 to some other strap or to the free end of the same strap. When the strap 11 is drawn rearwardly in the manner just mentioned, it is pulled firmly against the pin 10 so that the 80 strap and buckle cannot become disengaged. It will be obvious moreover, from an inspection of Fig. 3, that the end 12 being doubled under the part 11 above the bar edge, the end 12 is held firmly in place and there is 85 no liability of its becoming disengaged from the pin 10. It will be apparent however, that the buckle may be readily removed when it is desired to do so.

It will be apparent from the foregoing 90 that I provide a buckle which is both convenient and durable and which may be attached to said strap without the use of rivets or similar devices.

Having thus described my invention, 95 what I claim is:—

A buckle comprising in combination, a substantially rectangular frame, a plate integral with said frame and having a pin projecting downwardly from its lower surface, a prong on the upper surface of said plate and extending forwardly into engagement with said rectangular frame, a bow shaped piece attached to the underside of said frame substantially at the forward edge 105 of said plate, a cross bar attached to the

underside of said frame and having its upper surface substantially flush with the lower surface of said frame and spaced from the rear edge of said plate, and a second bow shaped member projecting upwardly from the top face of said frame at the rear thereof.

In testimony whereof I affix my signature in the presence of two witnesses.

ORIN F. DAY.
